ALTERNATING-CURRENT RECTIFIER.

1,081,641.

Specification of Letters Patent.

Patented Dec. 16, 1913.

Application filed May 12, 1913. Serial No. 767,126.

To all whom it may concern:

Be it known that I, EDWARD J. WIGGINS, a citizen of the United States, residing at Chicago, in the county of Cook and State of Illinois, have invented a new and useful Improvement in Alternating-Current Rectifiers, of which the following is a specification.

My invention relates to an improvement 10 in apparatus for converting alternating into direct electric currents.

The more important objects of my invention are to cause both sides of the line to be rectified without material loss of efficiency; to cause contact with the current-waves to be made and broken at the zero points and thus avoid sparking at the brushes; and to provide a construction of apparatus which shall be economical to 20 maintain, inasmuch as there are no parts to be renewed, such as the mercury-bulbs of a mercury rectifier and the platinum points of a vibrating rectifier.

In the accompanying drawing, Figure 1 25 is a plan view of my improved apparatus in the electric circuits including an alternating-current generator and shown diagrammatically; and Fig. 2 is a perspective view of the commutator used on the armature-shaft of the current-rectifying generator.

The motor 3 comprises a field formed of a magnet 4, the legs of which are wire-wound, as shown, the wiring being connected in series, as represented at 5; and the armature 6 is carried, to rotate in the field, on a shaft 7 journaled near its ends and provided with a fly-wheel 8. On an insulating cylinder 9 upon the shaft is carried the commutator formed of the two separated segments 10 and 11, the former being connected by a neck 10' with a ring 10² about the support, and the latter being connected by a neck 11' with a ring 11² about the same. On the shaft, at one side of the armature, is a metal collar 12 on which the armature is connected, and a similar collar 13 is on, but insulated from, the shaft at the opposite side of and connected with the armature. On one end of the shaft is a governor-device 14, shown as a bar 15 having balls 16 on its ends and fulcrumed at 17 on a bearing upon an ex-

tension 18 of the shaft and opposed by a spring 19 on the extension; and in the tubular outer end of the extension works a pin 20 having on its inner end a stud 21 projecting through a slot 22 in the extension into the path of the governor-bar. A throw-lever 23 is fulcrumed at one end on a bearing 24 and connected at its opposite end by a spiral spring 25 with an adjusting-screw device 26 for regulating the tension of the spring; and in the face of this lever is a socket 27 in line with the pin at 20 which the latter bears against the lever to throw it by the action of the governor-bar. A switch-lever 28 fulcrumed at 29, at one end, is connected by a short spiral spring 30 with the outer end of the throw-lever 23, whereby when, in the rotation of the shaft 7, it attains a certain speed, the bar 15 will advance the pin 20 against and turn the lever 23 beyond the perpendicular, when the pull of the spring 30 will carry the lever 28 to the opposite side of its throw. The switch-lever is formed with two alining end-sections, 28' and 28'', which are separated from each other and from the main body of the lever by insulation at 31 and 32; and these end-sections play between four contact jaws or members, 33, 34, 35 and 36, on one side, and four similar jaws, 37, 38, 39 and 40, on the opposite side.

At one side of the cylinder 9 two brushes, 41 and 42, contact, respectively, with the commutator-segment 10 and ring 10²; and a third brush 43 contacts with the ring 11² of the commutator-segment 11, with which a brush 44 contacts on the opposite side of the support. Brushes 45 and 46 contact, respectively, with the collars 12 and 13. The circuits may be traced as follows with the parts in their illustrated initial positions: An alternating-current generator 47 is indicated at 47. A wire *a* leads from one side of the generator to the contact-member 33, from which the lever-section 28' connects it with the wire *a'*, leading from the contact-member 34, to one side *w* of the direct current line and to a shunt-wire *a²* leading to one side of the field; and a branch-wire *a³* connects the shunt-wire with the brush 44. The other side, *w'*, of the direct-current line connects by a wire *b'* with the contact-member 35, which the

lever-section 28² connects with the contact-member 36, whence the return wire *b* goes to the generator; and the wire *w'* connects with the brush 41 and by a wire *b'* with the opposite side of the field.

- 5 With the generator 47 running and the switch-lever in its illustrated position, the branch circuit is closed, thus energizing the fields 4 of the motor 3 with alternating current of the frequency of the generator 47. The branch *a*³ supplies current to the armature 5, through slip rings 11² and 10², this current being initially of the frequency of the generator 47. Due to the interaction of 10 the armature field and its field coils the armature will begin to move. It has been found by practice that the effect of supplying current from the alternator 47 to the armature will in conjunction with the momentum of the fly wheel 8 cause the armature to be gradually accelerated until it synchronizes with the speed of the generator 47. When this speed has been reached the 15 governor actuates the throw-lever to snap the switch-lever into engagement with the other contact members. Then the course of the current is over wire *a* and a branch *a'* to the contact-member 40, and over lever-section 28², contact-member 39 and wire *c* 20 to the brush 43, and over ring 11², by way of the neck 11', commutator-segment 11, brush 44 and branch *a*³, to the side *w* of the direct-current line; and the return is over the side *w'* of the direct-current line to the 25 brush 41, commutator-segment 10, neck 10' and ring 10², brush 42, wire *b* to the contact-member 38, and over the lever-section 28' and contact-member 37 to the generator 47. At the connection of the branch *a*³ with 30 the line wire *W* a branch *a*² runs to the fields 4, completing a shunt circuit at brush 41 through wire *b*². It will be noted that, due to the synchronous operation of the commutator 9, direct current will thus be supplied to both the circuit *w w'* and the fields 35 4. The brush 45 is connected by a branch *c'* with the brush 41, and the brush 46 is connected by a wire *b*³ with the brush 42, so that the alternating circuit is closed through 40 the armature 5.

The reason I start the motor and bring its speed up until it is substantially synchronized with the speed of the generator, and then throw the switch into the running position, is because all the magnetic flux available is required in the field to raise the speed of the motor to substantially that of the generator 47, because alternating current is being delivered to the field, and the armature is receiving an interrupted alternating current. When however the motor attains the speed of the generator then direct current is supplied to the armature, the field however continuing to receive alternating current. When running under these condi-

tions it is to be noted that while the speed of the motor is substantially the same as the speed of the generator, the armature of the motor is in advance of the cycle of the generator. Now when the switch is thrown to 70 running position the strength of the field is reduced, because direct current is now delivered to the field, which is of a lower voltage than the alternating current, due to the spacing of the commutators, and alternating current is now delivered to the armature. This brings the armature back into step with the generator, and eliminates the 75 sparking of the commutator, because the current is broken at zero point.

80 Variation of voltage is controlled by winding the permanent field, as described, which keeps the armature in exact step with the cycles of the alternating current, since when the voltage rises it more strongly energizes 85 the magnet and produces a corresponding condition in the field.

As will be understood without illustration, the line-wires *w*, *w'*, which take the direct current from the commutator by the brushes, 90 lead to two binding posts, beyond which resistance may be placed in the line to give any desired amperage.

By means of the set-screw device 26, the 95 tension of the spring 25 may be regulated to vary, according to desire, the resistance of the lever 23 to the governor-action, to increase or decrease the number of shaft-revolutions for attaining the speed necessary to turn the switch; and the device thus 100 serves to regulate the machine according to the number of cycles of any particular alternating-current generator.

I realize that considerable variation is 105 possible in the details of construction thus specifically shown and described, and I do not intend by illustrating a single specific or preferred embodiment of my invention to be limited thereto; my intention being in the appended claims to claim protection 110 upon all the novelty there may be in the invention as broadly as the state of the art will permit.

What I claim as new and desire to secure by Letters Patent is—

1. In combination with an electric circuit, 115 an alternating-current generator and a rectifier for said current, comprising a magnet, a rotary shaft carrying an armature to rotate in the field of the magnet and a commutator, a set of commutator-brushes and armature-brushes connected with members of said set, a direct current line leading from the rectifier, and a switch-device operating in one position to start the rectifier 120 by the current from said generator, and in its other position to send said current through the rectifier upon the direct-current line.

125 2. In combination with an electric circuit, 130

an alternating-current generator and a rectifier for said current, comprising a wire-wound magnet, a rotary shaft carrying an armature to rotate in the field of the magnet and a commutator, a set of commutator-brushes and armature-brushes connected with members of said set, a direct current line leading from the rectifier, and a switch-device operating in one position to start the rectifier by the current from said generator and in its other position to send said current through the rectifier upon the direct-current line.

3. In combination with an electric circuit, an alternating-current generator and a rectifier for said current, comprising a magnet, a rotary shaft carrying an armature to rotate in the field of the magnet and a commutator formed of a pair of segments each having a ring about and insulated from the shaft and connected with the segment by a neck, a pair of brushes contacting the opposite segments and connected with the field, a pair of brushes contacting said rings and brushes on opposite sides of the armature connected with said ring-contacting brushes, a direct current line leading from the rectifier, and a switch-device operating in one position to start the rectifier by the current from said generator and in its other position to send said current through the rectifier upon the direct-current line.

4. In combination with an electric circuit, opposite sets of contact members, an alternating-current generator, and a rectifier for said current comprising a magnet, a rotary shaft carrying an armature to rotate in the field of the magnet and a commutator, a set of commutator-brushes and armature-brushes connected with members of said set, a direct current line leading from the rectifier, a switch supported to be moved from engagement with one set of said contact-members, to start the rectifier by current from said generator, into engagement with the other set thereof, to send said current through the rectifier upon the direct-current line, a governor on the shaft, and means

controlled by the governor for throwing the switch from one to the other of its positions. 50

5. In combination with an electric circuit, opposite sets of contact-members, an alternating-current generator, and a rectifier for said current, comprising a magnet, a rotary shaft carrying an armature to rotate in the field of the magnet and a commutator, a set of commutator-brushes and armature-brushes connected with members of said set, a direct current line leading from the rectifier, a switch-lever having insulating sections and supported to be turned from engagement with one set of said contact-members, to start the rectifier by current from said generator, into engagement with the other set thereof, to send said current through the rectifier upon the direct-current line, a throw-lever having a throwing spring-connection with the switch-lever, and a governor device on the shaft engaging the throw-lever to turn it and throw the switch-lever by a predetermined speed of the shaft's rotation.

6. In an alternating current rectifier, a magnetic member, a rotating armature therein, means for starting and means for 75 maintaining the speed of the armature, an adjusting device adapted to be set to regulate the speed to alternating currents of different cycles, and a switching device adapted to change the connections of the starting 80 means from an alternating source of current to connections carrying current rectified from such source.

7. In an alternating current rectifier, a magnetic member, a movable member, 85 means for accelerating the movable member to a given speed and means for maintaining such speed, comprising a switch device adapted to energize the magnetic member during the acceleration period with alternating current and with direct current when the given speed has been attained.
